**PROCEDURE AND APPARATUS FOR NITRIDING
FILM TYPE PRECISION RESISTORS**

Gaylord A. Swartz and William E. McLean, Independence, Kans., assignors to Electra Manufacturing Company, Kansas City, Mo., a corporation of Missouri

Filed Feb. 19, 1962, Ser. No. 173,975

3 Claims. (Cl. 148—16.6)

The present invention relates to manufacture of film type precision resistors and more particularly to means for nitriding films of chromium-titanium alloys or the like.

It is an object to provide a procedure and apparatus for nitriding alloyed films to produce a conductive coating which is stable, adherent and durable and to produce film type resistors capable of maintaining their physical and electrical qualities over long periods of time and even though subjected to severe operating conditions. It is another object related to the foregoing to provide a procedure and apparatus for nitriding films made of metallic alloys, for example, chromium and titanium, and which produces a substantially flat temperature coefficient of resistance over wide temperature swings. Consequently, it is an object to provide nitrided resistors capable of meeting the most stringent military and commercial specifications.

It is another object to provide a nitriding procedure and apparatus which is capable of handling large batches of individual elements, for example, resistor substrates, but which nevertheless assures uniform nitriding over each unit area of the elements being treated. It is a related object to provide a nitriding procedure and apparatus which permits treatment of the elements in bulk while still insuring a high degree of uniformity from unit to unit and which nevertheless provides a relatively short treatment cycle. Consequently it is an object to provide a procedure and apparatus for making nitrided film type resistors at low cost, a cost comparable to the cost of manufacturing conventional non-precision resistors.

Other objects of the present invention will become apparent upon reading the attached detailed description and upon reference to the drawings in which:

FIGURE 1 is a general perspective view of a portion of the nitriding apparatus constructed in accordance with the present invention.

FIG. 2 is a longitudinal section taken vertically through one end of the nitriding tube with a charge of resistor substrates in place.

FIG. 2a is a cross section taken along line 2a—2a in FIG. 2.

FIG. 3 is a diagram showing the means for supplying ammonia gas to the nitriding tube and the control system therefor.

While the invention has been described in connection with a preferred embodiment, it will be understood that we do not intend to be limited to the embodiment described, but intend to cover the various modified and alternative procedures and apparatus included within the spirit and scope of the appended claims.

Turning to the drawings, the preferred apparatus for practicing the invention includes a nitriding chamber generally indicated at 10 having connections 11, 12 at its ends. Preferably, the chamber is tubular and is of horizontally disposed U shape to facilitate movement into and out of a high temperature oven 15 having an opening 16. For the purpose of supporting the nitriding tube, a wheeled carriage 17 is provided having wheels 18 for riding on a pair of tracks 19. For sealing the opening 16 when the nitriding tube is inserted, the tube has a perpendicularly extending sealing plate 20. The plate may be made of metal having a refractory surface 21 of sheet asbestos or the like. A material is chosen for the tube 10 which is non-porous, refractory and inert and which has

2

a low temperature coefficient of expansion, fused quartz being preferred.

To permit loading of the nitriding chamber with resistor elements having a conductive alloy film thereon, the ends 11, 12 of the tube are preferably constructed as shown in FIG. 2. The end 11 will be taken as representative. In this figure, it will be noted that the refractory quartz portion of the tube terminates in a metallic sleeve 31 of brass or the like having a removable end cap 32 provided with a circular gasket 33 of heat resistant rubber. For maintaining the end cap firmly seated, a clamping yoke 34 is provided which is swingable to an out-of-the-way position upon a pair of pivot bolts 35, 36 tapped into the sleeve 31. Threaded into the yoke are clamping screws 37 which bear upon the outer surface of the end caps. Gas connections 38, 39 are provided in the cap 32, the connection 38 serving to conduct gas into the nitriding chamber and, in another portion of the cycle, to exhaust gas therefrom. Corresponding reference numerals, with subscript "a," apply to corresponding parts at the opposite end of the tube.

The sleeves 31, 31a and their junctions with the tube 10 are kept cool notwithstanding the high temperature within the oven by an air jacket 40 which lies next to the plate 20 and which surrounds the ends of the tube as shown. Inlet and outlet connections 41, 42 are provided and air flow is induced by any desired means.

To load the nitriding chamber with a charge of resistor elements, the elements indicated at 45 are stacked in a semi-circular tray 46 made of stainless steel or the like and which conforms to the curvature of the inner wall of the tube. It is convenient to stack the elements end to end in horizontal rows since the units are received from the vacuum chamber strung on lengths of wire. Moreover, this mode of stacking insures maximum utilization of the space within the tube. Similar trays 46 are placed in both legs of the U. While uniform stacking is preferred, it will be apparent that the invention is not limited thereto and that the resistor elements may be stacked randomly in the chamber. After the nitriding procedure, to be described in some detail below, has been completed the nitriding tube 10 is removed from the oven by retracting carriage 17 along the tracks 19. The clamping screws 37, 37a are released so that the yoke 34, 34a may be swung to one side. The caps 32, 32a are removed so that the trays of resistor elements may be withdrawn.

In accordance with the present invention means are provided for throttling ammonia gas from a source which is substantially above atmospheric pressure to a pressure which is substantially below that of the atmosphere for flowing through the nitriding chamber while the chamber is maintained at a high temperature in the oven 15. The ammonia gas used in the nitriding chamber is derived from an ammonia cylinder 50 which may have a pressure, at room temperature, on the order of 130 pounds per square inch. In the present instance throttling of gas to the nitriding chamber takes place in two steps. Thus throttling takes place first in the needle valve 51 and subsequently in a second needle valve 52. Use of two valves in this position is accompanied by several advantages. In the first place the range of pressure from approximately 130 pounds at the input to less than atmospheric at the output is so great that reliability is improved by throttling in two steps, from high pressure to intermediate pressure and from intermediate to low pressure. A further advantage resides in the fact that a flow meter 53 may be interposed between the two valves and, by relative adjustment of them, a pressure may be caused to exist at the flow meter which achieves maximum accuracy in the measurement of flow. Finally, use of two valves makes the throttling adjustment less critical than if all of the throttling had to be accomplished with a single valve.

Where most of the throttling effect is achieved with one of the valves, the other may be used to provide vernier adjustment.

In accordance with one of the aspects of the invention a vacuum pump is employed for exhausting gas from the nitriding chamber and a valve capable of throttling action is interposed between the chamber and the pump for providing additional control of the pressure in the chamber. In the present instance the vacuum pump, indicated at 55, has an associated valve 56 which may be a needle valve or valve of other design capable of throttling action. By proper relative adjustment of valves 51 and 52 on the one hand and valve 56 on the other, it will be apparent that almost any desired pressure below atmospheric may be established in the nitriding chamber for a given rate of flow. Moreover, by relative adjustment of all three of the valves the flow measuring device 53 and the nitriding chamber may both be operated at optimum pressure under given rate of flow conditions providing a high degree of flexibility of adjustment.

It may be noted that it is not essential that the valve 56 be of the throttling type provided that the line which leads from the nitriding chamber to the vacuum pump is tailored both in length and inside diameter so as to produce the desired amount of throttling action, in which case the valve 56 may be replaced by a simple valve of the on-off type.

In order to control the direction of gas flow through the nitriding tube, a four-way solenoid type valve 60 is interposed between the nitriding tube and the remainder of the system. Such valve has an inlet port 61, an outlet port 62 and switchable ports 63, 64. The valve 60 is of conventional type, capable of making either "straight through" or "cross" connections. Assuming a straight-through connection, gas at low pressure is fed via the needle valves 51, 52 into the first end 11 of the nitriding tube while gas is withdrawn from the second end 12 through valve 56 and vacuum pump 55.

To enable reversal of the direction of flow on a periodic or timed basis, a solenoid reversing timer 65 is employed to control the energization of the winding in the solenoid valve 60. Thus, in the case of a nitriding treatment of, say, one hour's duration, the ammonia gas may be caused to flow through the U tube in one direction for one half hour and in the reverse direction for the remaining half hour, thereby tending to equalize the treatment of all of the resistor elements in the tube. Or, if desired, the timer 65 may be so constructed as to energize the solenoid valve for shorter intervals, for example, so that flow takes place in one direction for a period of fifteen minutes and in the opposite direction for a period of fifteen minutes with two complete cycles in a period of one hour.

The degree of vacuum existing in the U tube 10 is measured by any desired type of vacuum gauge. In the present instance, a thermocouple type of vacuum gauge having a head 71 and an indicator 72 is employed for measuring high vacuum. A McLeod type vacuum gauge 73, well known to those skilled in the art, connected to the port 39, is employed to measure pressures greater than 1 mm. of mercury. The corresponding port 39a at the other end of the tube is unused and is sealed by a plug. A temperature indicating and control device 75 is associated with the oven 15 in order to maintain the temperature constant at a set value. Such control devices are also well known to those skilled in the art. Electric heating of the oven is preferred.

In a practical operating cycle, the resistor elements 45 stacked in trays 46 are inserted into each leg of the nitriding tube. Such stacking is preferably done with care since the alloy film on resistor elements is somewhat fragile prior to the nitriding operation. The end caps 32, 32a are then clamped in place at each end of the U tube.

In carrying out the present invention, the nitriding tube, prior to admission of ammonia gas at low pressure is

filled with ammonia gas at substantially atmospheric pressure, thereby to insure removal of all of the air from the nitriding chamber. To accomplish this, valve 52 is closed and the high vacuum is drawn in the nitriding tube 10 through valve 56. When the indicated pressure has reached the desired low level, the valve 56 is closed and the valve 52 is opened, along with valve 51, in order to supply a flushing charge of ammonia gas to the nitriding tube until the pressure in the tube builds up substantially to atmospheric. Following this, the valve 52 is again closed and the valve 56 opened so that the ammonia gas is drawn from the nitriding tube. This insures that any residual gas in the tube is ammonia gas. The valves are then adjusted so that ammonia gas flows through the nitriding tube at a pressure substantially below atmospheric pressure and at a predetermined rate of flow. The rate of flow is preferably about 1400 cubic centimeters per minute, although such rate may be anywhere within a range of about 500 to about 5000 cubic centimeters per minute. Under flow conditions the pressure in the nitriding tube is preferably about 7 to 9 millimeters of mercury, although, here again, some variation is permissible. Thus, the pressure may be anywhere between about 5 to about 20 millimeters of mercury without substantial sacrifice in the result obtained. The flow and pressure adjustment are preferably made with the nitriding tube in the oven and after the nitriding tube has been brought up to operating temperature. The temperature settable on the control device 75 is preferably about 1000° C. although successful operation may be achieved within the range of about 900 to 1200° C.

After the flow conditions have been maintained for about one half hour the solenoid reversing timer 65 energizes the solenoid valve 60 to switch the ports 63, 64 so that ammonia gas flows in end 12 of the U tube, being evacuated from end 11. After one hour the tube 10 is withdrawn from the oven. There is little benefit in maintaining the nitriding tube at elevated temperature for more than one hour. Stability of the film has been achieved by subjecting the resistor elements to treatment for as little as one half hour. However, continuing the nitriding conditions for a longer period, up to say, two hours, provides a safety margin and insures that nitriding has been carried to completion.

The nitriding tube is allowed to cool gradually at room temperature until it can be comfortably handled. The flow of ammonia gas is then stopped and the system is evacuated to $\frac{1}{2}$ mm. of mercury or less in order to get rid of the residual ammonia gas. The vacuum is then released following which the tube is opened for removal of the resistor elements.

It is found that one of the advantages of employing ammonia gas at pressures substantially below atmospheric, and within the range of about 5 to about 20 millimeters of mercury, is that the mean free path of the ammonia gas molecules is substantially increased over the value existing at atmospheric pressure. Consequently, the ammonia molecules have greater energy content and more complete conversion of the film is achieved than is possible using gas at atmospheric pressure. It has been found desirable to continue the constant flow of the low pressure ammonia gas during the entire nitriding period. Using the described procedure, complete nitriding is achieved even over those areas where the resistor elements are in contact. It is found that the nature of the nitriding film is improved over that obtained at atmospheric pressure. The films are uniformly hard and adherent with extremely good physical and chemical stability and minimum temperature coefficient of resistance.

We claim as our invention:

1. The process of nitriding film type resistor elements having a film of metal capable of being nitrided thereon which comprises placing a plurality of resistor elements in a nitriding chamber, flowing ammonia gas through said chamber at a pressure of approximately 5 to approxi-

mately 20 millimeters of mercury and at a rate within the range of about 500 to about 5000 cc. per minute, and maintaining the temperature in the chamber within a range of about 900 to about 1200°C. during the interval that the resistors are maintained at the elevated temperature and until the film has been converted to nitride form.

2. The process of nitriding film type resistor elements having a film of metal capable of being nitrided thereon which comprises placing a plurality of resistor elements in a nitriding chamber, evacuating the air from said chamber, flowing ammonia gas through the chamber at a pressure of approximately 5 to approximately 20 millimeters of mercury, and maintaining the temperature of the chamber within a range of about 900 to about 1200°C. during the interval that the resistor elements are maintained at the elevated temperature and until the film has been converted to nitride form.

3. The process of nitriding film type resistor elements having a film of metal capable of being nitrided thereon which comprises placing a plurality of resistor elements in a nitriding chamber, evacuating the air from said

chamber, charging the chamber with ammonia gas at a pressure of approximately 5 to approximately 20 millimeters of mercury, maintaining the temperature of the chamber within a range of about 900 to about 1200°C. until nitriding is complete and gradually replenishing the gas during the interval that the elements are maintained at the elevated temperature.
